PAPER ALIGNER FOR RECORDING MACHINES

Howard M. Fleming, West Orange, N. J., assignor
to Monroe Calculating Machine Company,
Orange, N. J., a corporation of Delaware

Application November 2, 1948, Serial No. 57,989

8 Claims. (Cl. 197—127)

1

The invention relates to paper aligners for recording machines, such for instance as a Monroe listing adding machine having a shiftable carriage provided with a platen and a pivotal front feed paper guide having an upper straight edge and pressure rolls engaging the platen to feed a paper work sheet during rotation of the platen. According to this invention there is provided a manipulable means for moving the paper guide to open throat and closed throat positions, as well as to an incomplete closed throat position, prior to moving the paper guide to complete closed throat position, to loosely frictionally grip said sheet between said rolls and the platen to permit manual adjustment of the work sheet with respect to said straight edge to align the last printed entry on said sheet. The manipulable means is also arranged to operate means for rotating the platen subsequently to moving the paper guide to complete closed throat position to feed the work sheet reversely from its direction of insertion but in normal line feeding direction for entry of a new item is given linear relation to said last entry. Another object is to provide a second manipulable means for adjusting the effective stroke of the pawl of a ratchet and pawl means for rotating the platen one line or alternatively two line feeding and consequent spacing of the printing lines of the work sheet. Other objects and advantages will appear hereinafter or will be obvious.

The invention consists in the novel construction and combinations of parts as hereinafter set forth in the claims.

In the accompanying drawings,

Figure 1 is a plan view of a listing adding machine having the invention applied thereto.

Figure 2 is a side view of the invention as applied, the carriage end frame being shown as partly broken away, the paper guide being shown in completely closed throat position, and the second manipulable means being shown in position as adjusted to shorten the effective stroke of the pawl for one line feeding of the work sheet.

Figure 3 is a section on the line 3—3, Figure 1, the carriage end frame being shown as partly broken away, the paper guide being shown in open throat position.

Figure 4 is a view similar to Figure 2, with parts omitted, showing the pawl of the ratchet and pawl means in the position assumed with the paper guide in the open throat position of Figure 3, the second manipulable means being shown in position as adjusted to lengthen the ef-

fective stroke of the pawl for two line feeding of the work sheet.

The invention is shown as applied to a Monroe listing adding machine, such for instance as disclosed in the Crosman Patent No. 1,946,572, dated February 13, 1934, modified in accord with the disclosure of the Crosman Patent No. 2,323,205 dated June 29, 1943, so far as the general type of machine and of the carriage are concerned.

In the drawings, the numeral 1 designates a shiftable carriage having mounted thereon a rotatable platen 2, and a front feed paper guide 3 pivoted at its lower end at 4 to the carriage end frames 5 and tending to fall by gravity from normal or closed throat position (Fig. 2) to open throat position (Fig. 3), said paper guide having pressure rolls 6 which when in closed throat position (Fig. 2) engage the platen to cause a paper work sheet 7 to be fed during rotation of the platen and having an upper straight edge 8, located when in closed throat position in horizontal alignment with the longitudinal axis of the platen.

Manipulable means are provided for moving said paper guide to open throat and to closed throat position in such a manner that prior to moving the paper guide to complete closed throat position, the paper guide is moved to incomplete closed throat position to loosely frictionally grip the work sheet 7 between said rolls and the platen in such a manner as to permit manual adjustment of said sheet with respect to said straight edge to align the last printed entry on the work sheet. The manipulable means is arranged to operate a ratchet and pawl means for rotating the platen, subsequently to moving the paper guide to complete closed throat position, to feed the work sheet reversely from the direction of insertion for entry of a new item in given linear relation to said last entry.

The manipulable means comprises two identical operating levers 9 secured to the ends of rock shaft 10 journaled in the carriage end frames 5. Levers 9 are connected together at their free ends by a handle bar 9' to form a bail for ready operation by the user of the machine. Each lever 9 is provided with an aperture 9'', bounded in part by an arcuate edge 11 concentric with its fulcrum and by upper and lower arcuate seats 12 forming an extension or continuation of the edge 11. The edge 11 and seats 12 of each lever are engaged by a roller 13 carried upon the upper end of an arm 14 extending upwardly from and fast to each end of a rock shaft 4. Accordingly,

when rollers 13 and arms 14 are moved by manipulation of levers 9, the paper guide is moved to one of its three positions. Said upper and lower seats are so disposed as to be engaged by roller 13 and serve to temporarily retain the paper guide in incomplete closed throat position and in open throat position respectively. The upper of said seats has a cam edge 15 intersecting said concentric edge to move the paper guide to complete closed throat position, as shown in Fig. 2, while the lower of said seats has a cam edge 15' to move the paper guide to incomplete closed throat position. If, due to friction or other causes, the paper guide has not been moved to open throat position by gravity as the levers 9 are moved upwardly, the lowermost edge of the opening 9' will engage rollers 13 and force them into the lower seats 12, and force the paper guide into open throat position. Prior to movement of the paper guide to complete closed throat position (Fig. 2) the paper guide is moved by manual movement of bar 9' to incomplete closed throat position (wherein said roller engages the upper of said seats) to loosely frictionally grip the work sheet between said rolls and the platen to permit manual adjustment of said sheet with respect to said straight edge.

Subsequently to movement of the paper guide to complete closed throat position and upon full depression or movement of handle 9' which connects levers 9 ratchet and pawl means for rotating the platen will function to line space the work sheet 7. For this purpose a pawl 16 having an offset portion 16'' for engaging ratchet 26 on platen shaft 22 is spring urged into contact with the ratchet. The pawl is pivoted at its forward end at 16'' to crank arm 17 fast on shaft 10, which shaft also carries levers 9 and is movable therewith. During the downward movement of levers 9 the pawl 16 will engage the teeth of the ratchet 26 and rotate the latter counterclockwise to feed the paper the desired distance as will be described. During forward movement of levers 9, rollers 13 travel along the concentric edges 11, that is, during said subsequent rotation of said platen, thus retaining the paper guide in closed throat position.

At the end portion of the effective stroke of said pawl a lower cam edge 19 of the pawl engages a fixed pin 20 to lift the pawl out of engagement with its ratchet wheel. Likewise during the first portion of the return or idle stroke of the pawl, this cam edge and pin engagement upholds the pawl from engagement with its ratchet, after which portion the pawl will drop into engagement with the ratchet.

A second manipulable means is provided for adjusting the effective stroke of the pawl for one line or alternatively two line feeding and consequent spacing of the printing lines of the work sheet to bring the last entry thereon to or alternatively above the printing line (designated at 26' on Figure 2 of the drawings). This means comprises a lever 21 fulcrumed upon the platen shaft 22 and having an upper extension 23 engageable by said pawl (Fig. 4) to uphold the pawl from engagement with its ratchet during a portion of its effective stroke.

In the movement of the paper guide from open throat to incomplete closed throat position, the pawl 16 which has a transversely offset free end 16'' for engagement with ratchet 26 will be moved less than the length of one tooth of its ratchet wheel, at the start of which movement the offset free end 16'' lies above the point of a

ratchet tooth (Fig. 4), whereby the pawl will be prevented from rotating its ratchet wheel and the platen during the movement of the paper guide from open throat to incomplete closed throat position.

The lever 21 is provided with an aperture 24 the upper and lower edges of which are contacted by said fixed pin 20 to limit the movement of said lever in both directions. Suitable means are provided to temporarily retain said lever 21 in either of its two positions comprising a spring-pressed ball (indicated at 23') seated in the adjacent carriage end frame 5 and engaging one or the other of two recesses 23'' of a lower extension of said lever.

A spring-urged detent pawl 25 engages the ratchet wheel 26 of said ratchet and pawl means to yieldably hold the platen in position as rotated.

20 I claim:

1. In a listing adding machine having a shiftable carriage provided with a platen and a pivotal front-feed paper guide having an upper straight edge and pressure rolls engaging the platen to cause feeding of a work sheet during rotation of the platen; manipulable means for moving said paper guide to open throat position, to closed throat position, and to incomplete closed throat position prior to moving the paper guide to complete closed throat position, to loosely frictionally grip the work sheet between said rolls and the platen to permit manual adjustment of the work sheet with respect to said straight edge to align the last printed entry on said sheet, and means operable by said manipulable means for rotating the platen subsequently to moving the paper guide to complete closed throat position to feed the work sheet for entry of a new item in given linear relation to said last entry.

2. In a listing adding machine having a shiftable carriage provided with a platen and a pivotal front-feed paper guide having an upper straight edge and pressure rolls engaging the platen to cause feeding of a work sheet thereover during rotation of the platen; manipulable means for moving said paper guide to open throat position to closed throat position and to incomplete closed throat position prior to moving the paper guide to complete closed throat position to loosely frictionally grip the work sheet between said rolls and the platen to permit manual adjustment of the work sheet with respect to said straight edge to align the last printed entry on said sheet, ratchet and pawl means operable by said manipulable means for rotating the platen subsequently to moving the paper guide to complete closed throat position to feed the work sheet for entry of a new item thereon, and a second manipulable means for adjusting the effective stroke of the pawl of said ratchet and pawl means for one line or alternatively two line feeding of the work sheet.

3. In a listing adding machine having a shiftable carriage having a platen and a pivotal front-feed paper guide provided with an upper straight edge and pressure rolls engaging the platen to cause feeding of a work sheet thereover during rotation of the platen; manipulable means for moving said paper guide to open throat position, to closed throat position, and to incomplete closed throat position prior to moving the paper guide to complete closed throat position to loosely frictionally grip the work sheet between said rolls and the platen to permit

manual adjustment of said sheet with respect to said straight edge to align the last printed entry on said sheet, means operable by said manipulable means for rotating the platen subsequently to moving the paper guide to complete closed throat position to feed the work sheet for entry of a new item in given linear relation to said last entry, and means for temporarily retaining the paper guide in open throat and in complete closed throat position.

4. In a listing adding machine having a shiftable carriage having a platen and a pivotal front-feed paper guide provided with an upper straight edge and pressure rolls engaging the platen to cause feeding of a work sheet there-over during rotation of the platen, said paper guide tending to drop by gravity to open throat position; manipulable means for moving said paper guide to open throat and to closed throat position comprising a lever having an aperture bounded in part by an edge concentric with its fulcrum and by upper and lower seats, said paper guide having an upper extension bearing a roller, the lower of said seats being engaged by said roller when said paper guide is in open throat position, the upper of said seats being so disposed as to cause movement of the paper guide to incomplete closed throat position prior to movement of the paper guide to complete closed throat position to loosely frictionally grip said sheet between said rolls and the platen to permit manual adjustment of the work sheet with respect to said straight edge to align the last printed entry on said sheet, said lower and upper seats serving to temporarily retain the paper guide in open throat and in incomplete closed throat position, the upper of said seats having a cam edge intersecting said concentric edge to move the paper guide to complete closed throat position, and ratchet and pawl means operable by said manipulable means for rotating the platen subsequently to moving the paper guide to complete closed throat position to feed the work sheet for entry of a new item in given linear relation to said last entry, said roller travelling along said concentric edge during said subsequent rotation of the platen.

5. In a listing adding machine having a shiftable carriage having a platen and a pivotal front-feed paper guide provided with an upper straight edge and pressure rolls engaging the platen to cause feeding of a work sheet there-over during rotation of the platen, said paper guide tending to drop by gravity to open throat position; manipulable means for moving said paper guide to open throat and to closed throat position comprising a lever having an aperture bounded in part by an edge concentric with its fulcrum and by upper and lower seats, said paper guide having an upper extension bearing a roller, the lower of said seats being engaged by said roller when said paper guide is in open throat position, the upper of said seats being so disposed as to cause movement of the paper guide to incomplete closed throat position prior to movement of the paper guide to complete closed throat position to loosely frictionally grip said sheet between said rolls and the platen to permit manual adjustment of the work sheet with respect to said straight edge to align the last printed entry on said sheet, said lower and upper seats serving to temporarily retain the paper guide in open throat and in incomplete closed throat position, the upper of said seats having a cam edge intersecting said concentric edge to

move the paper guide to complete closed throat position, and ratchet and pawl means operable by said manipulable means for rotating the platen subsequently to moving the paper guide to complete closed throat position to feed the work sheet for entry of a new item thereon, said roller travelling along said concentric edge during said subsequent rotation of the platen, and a second manipulable means for adjusting the effective stroke of the pawl of said ratchet and pawl means prior to manipulation of said first named means for one line or alternatively two line feedign of the work sheet, comprising a lever fulcrumed upon the platen shaft and having an upper extension engaging said pawl to lift it from engagement with the ratchet during a portion of its effective stroke.

6. In a listing adding machine having a shiftable carriage provided with a platen and a pivotal front-feed paper guide having an upper straight edge and pressure rolls engaging the platen to cause feeding of a work sheet during rotation of the platen; manipulable means for moving said paper guide to open throat position, closed throat position, and to incomplete closed throat position prior to moving the paper guide to complete closed throat position, to loosely frictionally grip the work sheet between said rolls and the platen to permit manual adjustment of the work sheet with respect to said straight edge to align the last printed entry on said sheet, and means operable by said manipulable means for rotating the platen subsequently to moving the paper guide to complete closed throat position to feed the work sheet for entry of a new item in given linear relation to said last entry, said latter means being inoperable to rotate the platen during movement of said paper guide from open throat to incomplete closed throat position.

7. In a listing adding machine having a shiftable carriage provided with a platen and a pivoted front feed paper guide having pressure rolls engaging the platen when said guide is in normal or closed throat position to cause feeding of a paper work sheet during rotation of the platen; means comprising an operating lever for retaining the paper guide in normal closed throat position, for moving it to and retaining it in open throat position, for moving it to and retaining it in incomplete closed throat position, and for returning it to normal position; and means operable by said lever for subsequently rotating the platen, said latter means comprising a shaft actuated by said lever, ratchet and pawl means, and a crank arm fast on said shaft and having a pivotal connection with the pawl of said ratchet and pawl means.

8. In a listing adding machine having a shiftable carriage provided with a platen and a pivoted front feed paper guide having an upper straight edge and pressure rolls engaging the platen when said paper guide is in normal closed throat position to cause feeding of a paper work sheet during rotation of the platen; means comprising an operating lever for retaining the guide in normal position, for moving it to and retaining it in open throat position, for moving it to and retaining it in incomplete closed throat position, and for restoring it to normal position; means operated by said lever for subsequently rotating the platen, said latter means comprising ratchet and pawl means, a shaft operated by said lever, and a crank arm fast on said shaft, and pivotally connected to said pawl; and ma-
